(57) **CLAIM**

The ornamental design for a tool-shaped bubble toy, as shown and described.

DESCRIPTION

FIG. 1 is a perspective view of a tool-shaped bubble toy showing my new design;

FIG. 2 is a left side view thereof;

FIG. 3 is a right side view thereof;

FIG. 4 is a front view thereof;

FIG. 5 is a rear view thereof;

FIG. 6 is a top view thereof; and,

FIG. 7 is a bottom view thereof.

The broken lines are included for the purpose of illustrating portions of the bubble toy that form no part of the claimed design. The appearance within the unshaded regions within and immediately surrounding the broken lines likewise form no part of the claimed design.
